BANJO

Filed Nov. 11, 1922

FIG. 1.

FIG. 2.

FIG. 3.

FIG. 4.

Witnesses: Inventor:
H. Badian William L. Lange,
H. D. Penney By his Atty, P. H. Richards.

UNITED STATES PATENT OFFICE.

WILLIAM L. LANGE, OF NEW YORK, N. Y.

BANJO.

Application filed November 11, 1922. Serial No. 600,379.

This invention relates to banjos and similar musical instruments, the main object of which is to provide a device of this kind which will give a loud, clear tone of excellent quality.

Another object of the invention is to provide an instrument having means, adjustable at the will of the player, for modifying the tone as desired, sharpening its quality thereby to give an increased carrying quality or increasing the sonority to full tone quality, thereby qualifying the instrument to meet the requirements of large or small auditoriums, the character of the music played, and to fill its part in orchestral work.

Another object of the invention is to provide a device of this kind having an improved means for tensioning the diaphragm. Other objects of the invention are to improve generally the simplicity and efficiency of such devices and to provide a device or apparatus of this kind which is durable, economical to manufacture, and which will not get out of order.

The inventive features for the accomplishment of these and other objects are shown in connection with an improved musical instrument which, briefly stated, comprises a frame having upper and lower spaced rims and a transverse member secured across the center thereof. A sound reflector having a base portion mounted on the lower rim has an upturned outer flange for reflecting sound issuing between said rims. Between said base portion and upper rim hooks are provided for tensioning a diaphragm which is mounted over a tensioning ring supported by said upper rim. Downwardly disposed springs mounted on the inner part of the frame have their lower ends contacting with a disk-shaped back plate movable up and down in said lower rim against said springs and adjusted by a screw stud having engagement with said back plate and transverse member.

Other objects of the invention will appear as the description proceeds; and while herein details of the invention are described, the invention is not limited to these, since many and various changes may be made without departing from the scope of the invention as claimed.

In the accompanying drawing, showing by way of example two of many possible embodiments of the invention,

Fig. 1 is a plan of the instrument;

Fig. 2 is a bottom view of the instrument showing one form of the invention;

Fig. 3 is a sectional view of the form of Fig. 2, taken on the line 3—3 of Fig. 1, looking in the direction of the arrow of said line; and

Fig. 4 is a similar sectional view, partly in elevation, of another form of the invention.

As shown in Figs. 1 to 3, one form of my invention comprises a frame having an upper rim 11 and a lower rim 12 spaced apart to form therebetween a sound outlet opening 13. A neck 14 (Fig. 2) is secured to said rims 11 and 12 and has a dowel extension 15 extending transversely across the frame above the level of the lower rim 12 and having a central vertical bore 18, Fig. 75. An annular resonator reflector, generally denoted by 20, has a vertical outer flange 21 cut-away, as at 22, Fig. 2, to receive the neck 14 and a substantially horizontal base portion 25 provided between 80 its peripheral portions with hook-receiving openings 26 and having its inner peripheral portion resting on top of the lower rim 12. Studs or uprights 27 passing through said base portion 25 and mounted in and connecting said rims 11 and 12, receive thereon nuts 28 engaging said upper rim 11 and base portion 25 to hold the parts locked. The studs 27 and nuts 28 divide the opening 13 into a plurality of intermediate lateral sound 90 outlets.

Vertical rods or supports 30 in the top of the upper rim 11 support a tone ring 32, holding the ring slightly spaced above the upper rim 11. A diaphragm or vellum 33, 95 tensioned over said tone ring 32, is drawn down at the edges and terminates with a flesh hoop 34, and a tension ring 36 is mounted on said flesh hoop 34 and provided with an upper groove 38 into which the hooked upper ends of tensioning rods 40 engage, the lower ends of said rods 40 being threaded and passing through said hook-receiving openings 26 of said base portion 25 with nuts 42 on said ends for tensioning 105 the diaphragm 33.

Downwardly and inwardly disposed springs 44 are mounted on the inner part of the upper rim 11, their free ends in contact with a disk-shaped downwardly convexed 5 upwardly concaved tone modifier, sound damper or regulator 45 having a thickened peripheral edge, as 46, to engage the inner face of the lower rim 12, whereby the plate may be adjustably pressed inwardly against 10 the springs 44 or outwardly by said springs.

A boss plate 48 having a central threaded opening 49, coaxial with said bore 18, is suitably secured on the lower face of said extension 15, and a threaded adjusting stud 15 50, having a knurled head 54, passes through the central perforation 51 of tone modifier 45 and into said bore 18 and threaded openings 49, whereby as the stud 50 is screwed home the tone modifier 45 may be adjusted 20 to the upper edge of the lower rim 12 for providing a sharp, far-carrying tone, while as the adjusting stud 50 is withdrawn, the tone modifier 45 will be moved to the lower edge of the lower rim 12 by means of the 25 springs 44 and thus provide a full sonorous tone, intermediate positions of the tone modifier providing intermediate tones.

In Fig. 4 there is shown another form of sound-board adjusting means, in which the 3 upper rim 11' is provided with inwardly projecting lugs 60 having downwardly opening recesses 61 therein, while tone modifier 45' is provided with upwardly opening recesses 62. Between top rim 11' and back plate 45' there are mounted a plurality of helical springs 63, retained in position by having their opposite ends projecting in said recesses 61 and 62, and serving a purpose similar to the springs 44.

40 The sound from the interior of the instrument passes over the upper edge of the rim 11' (Fig. 4) through the upper lateral sound outlets formed between the tone ring 32 and said upper edge and thence downwardly exteriorly of the rim 11' between said rim 11' and the ring 36, to the resonator reflector 20 for emission to the atmosphere. The space within the frame constitutes a 45 tone chamber communicating through the intermediate sound outlet 13 with the resonator reflector 20.

50 By upward or downward movement of the tone modifier the volume of this chamber is reduced or increased, the tone of the instrument being modified accordingly as previously stated, and an instrument is qualified to meet the requirements as to tone of a large or small auditorium, the character of music played, and for appropriately filling the part of the instrument in orchestral work.

55 For the purposes of description in this specification and claims, the part of the instrument toward the diaphragm is considered the upper part.

Having thus described my invention, I claim:

1. A sound instrument comprising a frame provided with lateral sound outlets above the lower edge; and establishing free communication between the interior of the instrument and the exterior atmosphere; a diaphragm tensioned over said frame; and a sound deflector secured around said frame below said outlets and having an upwardly extended outer portion. 75

2. A sound instrument comprising a frame provided with lateral sound outlets between the upper and lower edges; and establishing free communication between the interior of the instrument and the exterior atmosphere; a diaphragm tensioned over said frame; and a sound deflector having a base secured around said frame as low as the lower part of said outlets and having an upwardly extended outer flange. 80

3. A sound instrument comprising a frame provided with upper lateral sound outlets near the upper edge of the frame and intermediate sound outlets about midway between the upper and lower edges; and establishing free communication between the interior of the instrument and the exterior atmosphere; a diaphragm tensioned over said frame; and a sound deflector having a base secured around said frame at the lower part of said intermediate outlets and having an upwardly extended outer flange extending to about to the top plane of the instrument. 95

4. A sound instrument comprising a frame provided with upper lateral sound outlets near the upper edge of the frame; and establishing free communication between the interior of the instrument and the exterior atmosphere; a diaphragm tensioned over said frame and terminating in a tension ring spaced from said outlets and extending below the outlets; and a sound deflector having a base secured around said frame and having an upwardly extended outer flange spaced from and extending above the lower part of said tension ring. 105

5. A sound instrument comprising a frame provided with upper lateral sound outlets near the upper edge of the frame and intermediate sound outlets about midway between the upper and lower edges; and establishing free communication between the interior of the instrument and the exterior atmosphere; a diaphragm tensioned over said frame and terminating in a flesh hoop; a tension ring on said hoop spaced from said upper outlets and extending below said upper outlets; and a sound deflector having a base secured around said frame at the lower part of said intermediate outlets and having an upwardly extended outer flange spaced from and extending above the lower part of said tension ring. 115

6. A sound instrument comprising a frame; a diaphragm over said frame; a resonator; and means for adjusting the resonator adjustable to different operative positions toward and from the diaphragm and holding it operatively steady in said positions. 70
7. A sound instrument comprising a frame; a diaphragm over said frame; a resonator within said frame; and means for adjusting the resonator toward and from the diaphragm and holding it operatively steady in the different adjusted positions. 75
8. A sound instrument comprising a frame provided with lateral sound outlets above the lower edge; a diaphragm tensioned over said frame; and a resonator adjustable within said frame between the sound outlets and the lower edge. 80
9. A sound instrument comprising a frame; a diaphragm over said frame; a resonator at the lower part of said frame adjustable to different positions toward and from said diaphragm; and means for steady- 85
- 20 25 ing the edge of the resonator in said different positions. 90
10. A sound instrument comprising a frame provided with lateral sound outlets; a diaphragm over said frame; an adjustable resonator at the lower part of said frame; and springs pressing on the resonator for steady- 95
- 30 35 ing the resonator. 100
11. A sound instrument comprising a frame provided with intermediate sound outlets; a diaphragm over said frame; a resonator adjustable within said frame between the sound outlet and the lower edge; means for adjustably drawing the resonator toward the diaphragm; and springs press- 105
- 40 45 ing on the resonator for moving it away from said diaphragm and for steady- 110
12. A sound instrument comprising a frame provided with lateral sound outlets; a diaphragm over said frame; and a resonator adjustable within said frame while remote from said outlets. 115
13. A sound instrument comprising a frame provided with lateral sound outlets; a diaphragm over said frame; a resonator at the lower part of said frame; and means for adjusting the resonator toward and from the diaphragm while the size of the outlets remains constant. 120
14. A sound instrument comprising a frame provided with lateral sound outlets; a diaphragm over said frame; a sound deflector secured around said frame as low as the lower part of said sound outlets and having an upwardly extending outer flange; and a resonator at the lower part of said frame adjustable independently of said deflector. 125
15. A sound instrument comprising a frame provided with lateral sound outlets; 130
- a diaphragm over said frame; a sound deflector secured around said frame at the lower part of said frame and having an upwardly extended outer portion; and a resonator adjustable at the lower part of said frame. 135
16. A sound instrument comprising a frame provided with lateral sound outlets between the upper and lower edges; a diaphragm over said frame; tensioning means for said diaphragm; a sound deflector secured around said frame at the lower part of said sound outlets and having an upwardly extended outer portion; and a resonator adjustable within said frame independently of the tensioning means. 140
17. A sound instrument comprising a frame provided with lateral sound outlets between the upper and lower edges; a diaphragm over said frame; a sound deflector secured around said frame at the lower part of said sound outlets and having an upwardly extending outer portion; and a resonator adjustable within and independently of said frame. 145
18. A sound instrument comprising a frame comprising upper and lower spaced rims providing sound outlets therebetween; a diaphragm tensioned over said upper rim; and a sound deflector secured on the upper face of said lower rim and having an upwardly extended outer flange spaced from the upper rim. 150
19. A sound instrument comprising a frame; a diaphragm over said frame; a tension ring tensioning said diaphragm; an annular member secured exteriorly around said frame; and tension rods tensioned between said tension ring and member and passing between parts of said member. 155
20. A sound instrument comprising a frame; a diaphragm over said frame; a tension ring tensioning said diaphragm; an annular member secured around said frame; tension hooks engaging said tension ring and having threaded lower ends extending through said member; and nuts on said lower ends. 160
21. A sound instrument comprising a frame provided with intermediate lateral sound outlets; a diaphragm over said frame; a tension ring for said diaphragm; a sound deflector having a base secured around said frame at the lower part of said outlets and having an upwardly extended outer portion; tension hooks engaging said tension ring and having threaded lower ends extending through said base; and nuts on said lower ends. 165
22. In combination, a banjo frame comprising upper and lower spaced rims and having a transverse member; downwardly disposed springs mounted on the inner part of the frame; a disk-shaped concavo-convex member having a thickened peripheral edge 170

engaging the inner face of the lower rim, and disposed against said springs; whereby said member may be adjustably pressed inwardly against the springs or outwardly by the springs. 25

23. In combination, a banjo frame comprising upper and lower spaced rims; a transverse member secured across the center of the frame, a sound deflector having a base portion mounted on the lower rim and an upturned outer flange; a diaphragm drawn over the upper rim and having a peripheral tension ring; hooks tensioned between said base portion and ring; downwardly disposed springs mounted on the inner part of the frame; a disk-shaped member movable up and down in said lower rim against said springs; and an adjusting stud having engagement with said movable member and transverse member. 20

24. In combination, a banjo frame comprising upper and lower spaced rims, a sound deflector having a base portion mounted on the lower rim and an upturned outer

flange; a diaphragm drawn over the upper 25 ring and having a peripheral tension ring; and hooks tensioned between said base portion and ring.

25. In combination, a banjo frame comprising upper and lower spaced rims, a 30 transverse member secured across the center of the frame; a plurality of inwardly and downwardly pointing flat springs secured at their upper ends to the inner face of the upper ring provided with downwardly horizontally and upwardly curved lower ends; a disk-shaped concavo-convex member having a thickened peripheral edge provided with a cushion to engage the inner face of the lower rim and pressed upon by said lower ends of said springs, whereby said member may be adjustably pressed inwardly against the springs or outwardly by the springs; a diaphragm drawn over the upper rim; and an adjusting stud having 40 engagement with the concavo-convex member and transverse member. 45

WILLIAM L. LANGE.
